CLAIM

The ornamental design for a display screen or portion thereof with graphical user interface, as shown and described.

DESCRIPTION

The sole FIGURE is a front view of a display screen or portion thereof with graphical user interface showing my new design.

The outermost perimeter broken line in the FIGURE illustrates a display screen or portion thereof and forms no part of the claimed design.

The remaining broken lines in the FIGURE depict portions of the graphical user interface which form no part of the claimed design.

The horizontal bands of continuous solid vertical line segments within the lower round-cornered rectangles form part of the claimed design.
